UNITED STATES PATENT OFFICE

RUDOLF MUNDLOS, OF MAGDEBURG, GERMANY

DRIVING GEAR FOR MATERIAL FEEDERS FOR SEWING MACHINES

Application filed January 10, 1928, Serial No. 245,759, and in Germany November 18, 1926.

This invention relates to sewing machines by means of which two thread lock stitches and zig-zag lines of stitches can be made, i. e. in which the material-feeder executes a 5 movement in the longitudinal direction of the machine, a movement transversely to the first movement, and a reciprocating movement in vertical direction.

The invention has for its object to improve 10 the driving mechanism for the material-feeder for such machines as have means for producing a reciprocating movement in vertical direction by means of a cam or finger on the main shaft, situated underneath the 15 material-feeder, and it has also been proposed to derive from the oscillating shaft the movement of the material-feeder transversely to the longitudinal direction of the machine. The driving mechanisms of known type do not 20 work accurately enough as they comprise too great moving masses, which render the working of the machine unsteady.

According to the invention the longitudinal shifting of the material-feeder is produced by an oscillating link which transmits 25 its movement by a connecting rod upon a rocking shaft adapted to be shifted in longitudinal direction. Owing to the rocking movement of this shaft the connecting rod 30 must be composed of two parts, the one part of the rod being rotatable in the other part of the rod but not shiftable in longitudinal direction. The connecting rod acts on one of two arms arranged on the rocking shaft 35 and designed as bearings for a pivot bolt over which grips a sleeve of the holder of the material-feeder.

By the longitudinal movement of the rocking shaft a longitudinal movement is imparted also to the material-feeder, a transverse movement of the material-feeder being produced by the rocking movement of the 40 rocking shaft.

When the size of the moving masses, which 45 is small in this form of construction, has to be reduced to a minimum, not the whole rocking shaft, but only the short portion of the same which carries the oscillatable arms is made movable in longitudinal direction.

50 An embodiment of the invention is il-

lustrated, by way of example, in the accompanying drawing, in which:

Fig. 1 is a rear-elevation of the machine.

Fig. 2 is a plan-view of the same, viewed from below.

Fig. 3 shows a constructional detail on enlarged scale.

The main shaft 1 is journaled in two bearings 2 and 3 which are fixed on the machine frame. On this main shaft a pinion 4 is keyed which meshes with a spur wheel 6 held in a bearing 5. Rigid with this spur wheel 6 is a cam disk 7 which guides a stud 9 of a link 10. The link 10 is pivotally maintained by a stud 8 and is oscillated when the bolt is moved by the cam disk 7. A connecting rod is composed of two parts 11 and 11^a, the part 11^a of said connecting rod being connected directly with an arm 12 on a shaft 13^a. The arms are reciprocated by the two part connecting rod, the part 11 being maintained in position to which it has been adjusted, and its head 11^c is so constructed as to provide a bore 11^c and a cavity 11^e. The reduced end which passes through the bore 11^c has a screw threaded end portion which is engaged by a nut 11^d which is located in the cavity 11^e. The nut 11^d connects the parts so that the part of the rod 11^a can turn in the head 11^c, but not execute a movement in longitudinal direction with regard to the rod 11.

The part 11^a of the rod has at its front end a head 11^b which grips or surrounds a portion of one of the arms 12 on the rocking shaft 13^a. The cam groove in the disk 7 actuates the link 10 and the connecting rod 11, 11^a. An oscillating movement is communicated to the arm 12 through connections to the member 24. The rotative part 11^a of the rod allows the arm 12 to oscillate freely. The arm 12 being rigid with the rocking shaft 13^a, this shaft is shifted by the movement of the rod 11. The part 13^a of the rock shaft 13 has thereon the arms 12 which carry a bar 20, upon which is mounted a part 21 of a material feeder. The part 13^a of the shaft 13 is reciprocatorily longitudinally by the cam 7 and link 10 to reciprocate the material feed to produce zigzag stitches 100

of a length which may be varied in accordance with the setting of the rod in the slot of the link 10 by which the length of reciprocation of the part 13^a of the shaft is effected.

- 5 In order that the mass to be moved does not become too great, one can, as shown in Fig. 1, make the shaft 13 in two parts. The one part 13 is not shiftable in longitudinal direction and executes merely a rocking movement. The part 13^a is mounted on the bolt 14 so that it can be shifted in longitudinal direction and is connected to the part 13 by a coupling 16, 17. The part 13^a of the shaft has an arm 16 on which a bolt 17 is fixed. 10 This bolt 17 projects through an arm 18 of the part 13 of the rocking shaft, said arm having, same as the part 13^a, a bore designed to receive the bolt 15. The shaft is held at the middle by a bearing 19. 15 20 The pivot-bolt 20, mounted in the two arms 12, carries a sleeve 21 to which the material-feeder 22 is fixed. The to and fro movement of the material-feeder 22 is produced by the connecting rod 11, acting upon the arms 12 of the rocking shaft 13. 25

To the material-feeder a movement transversely to the longitudinal direction is communicated at the same time through the oscillating movement of shaft 13 and consequently of the arms 12 and bolt 20. The movement of the material-feeder is controlled by a cam 23 on the main shaft 1. The rocking shaft 13 is driven, in a manner known per se, from the main shaft by a lever system 30 which acts upon a lever 24 of said shaft 13. 35

I claim:

- In a driving gear for the material-feeder in sewing machines, the combination in mechanism for imparting to the material-feeder a movement in longitudinal direction, 40 consisting of an oscillatable link, a rocking shaft, composed of one part which is not shiftable and of another part which is shiftable, two arms on said shiftable part of said shaft, a connecting rod connecting one of said arms with said link and composed of two parts one part mounted in the other so that it can rotate with regard to the same but not carry out a shifting movement, a cross bar 45 carried by the said arms of said rocking shaft, and a material feed bar associated with the cross bar. 50

In testimony whereof I affix my signature.

RUDOLF MUNDLOS.
